US00D616439S

(12) **United States Design Patent**
Mugica et al.

(10) **Patent No.:** US D616,439 S
(45) **Date of Patent:** ** May 25, 2010

(54) **SMART BIOMETRIC DATA CAPTURE
SUB-ASSEMBLY**

(75) Inventors: **Antonio Mugica**, Caracas (VE); **Roger Pinate**, Caracas (VE); **Paul Babic**, Caracas (VE); **Jorge M. Vasquez**, Weston, FL (US); **Romano Stasi**, Weston, FL (US); **Paul Chen**, Taipei (TW); **Ernesto Vecchi**, Tomball, TX (US); **German Dorta**, Caracas (VE); **Dimas Ulacio**, Caracas (VE); **Dany Farina**, Caracas (VE); **Luis Coronel**, Caracas (VE); **Fabiola Arrivillaga**, Caracas (VE)

(73) Assignee: **Smartmatic International Corporation**, St. Michael (BB)

(**) Term: **14 Years**

(21) Appl. No.: **29/338,849**

(22) Filed: **Jun. 19, 2009**

(51) **LOC (9) Cl. 14-02**

(52) **U.S. Cl. D14/383; D14/384**

(58) **Field of Classification Search .... D14/314, D14/420, 421, 424, 383-387; D18/4.1-4.4; D24/185, 186; 235/51, 54 F, 375, 380, 382, 235/382.5, 462.45, 470; 345/179; 361/679.41; 600/301; 355/64, 65, 75, 81; 382/124-126**

See application file for complete search history.

(57) **CLAIM**

The ornamental design for a smart biometric data capture sub-assembly, as shown and described.

DESCRIPTION

FIG. 1 is a perspective view of a smart biometric data capture sub-assembly;

FIG. 2 is a front view thereof;

FIG. 3 is a top view thereof;

FIG. 4 is a right side view thereof;

FIG. 5 is a left side view thereof;

FIG. 6 is a rear view thereof; and,

FIG. 7 is a bottom view thereof.

The broken lines depict environmental subject matter only and form no part of the claimed design.
